LIQUID-FUEL STOVE.

1,274,134.

Specification of Letters Patent. Patented July 30, 1918.

Application filed April 18, 1918. Serial No. 229,254.

To all whom it may concern:

Be it known that we, JOHN S. BRENNAN and ALBERT J. LINDEMANN, citizens of the United States, and residents of the city of Milwaukee, in the county of Milwaukee, State of Wisconsin, have invented certain new and useful Improvements in Liquid-Fuel Stoves, of which the following is a specification.

10 The improvements relate to liquid fuel stoves and particularly to such as are ordinarily employed in the burning of liquid hydrocarbons such as kerosene, and its objects are, among others, to provide an improved 15 liquid fuel stove in which the combustion in each burner may be started, regulated and extinguished by regulation of the oil supply and without employing a cotton wick. Such burners are commonly called wickless 20 burners, and are provided with a relatively shallow fuel trough having therein a short wick of asbestos, or other incombustible absorbent, from which the liquid hydrocarbon is vaporized. Blue-flame combustion tubes 25 are also usually provided and are seated on the upper edges of the trough. The use of the devices here in question is not limited, however, to burners of this particular character. In the embodiment of the invention 30 herein described and shown the fuel is regulated by means of devices which raise and lower the burner trough with respect to the maintained oil level of the reservoir, thereby controlling the depth of liquid in the 35 trough or draining it, and in this manner the use of valves for that purpose, with their attendant disadvantages is dispensed with.

Stoves of this general character have been employed for many years, but so far as is 40 known are open to one or more of the following objections. Where the tube leading up to the burner trough is arranged to slide or telescope in a tube leading up to it, and a stuffing box is required, leakage often results, either from deterioration of the packing or injury to the tubes or the stuffing box, or from some other cause. Where the reservoir and burner are connected by a rigid pipe and one or the other or both raised or 45 lowered, it is necessary to provide a reservoir or tank for each burner, or the burners cannot be separately regulated, where a plurality of burners are employed. This con-

struction also necessitates a slight tilting movement of one part or the other and a corresponding disturbance of the oil level therein. These objections apply whether the parts are mounted to have a rocking motion or the flexibility of the supply pipe is depended upon. In all forms, the fact that 55 the trough with its superimposed burner parts or the reservoir is vertically movable gives rise to the danger that it will be moved accidentally, and the fluid level thus changed unintentionally; and the adjustable mounting of the parts is attended with the inherent objection that they are not as strong or as stable as they would be if rigidly and immovably supported. The present improvements are designed to overcome these 60 and other objections, and to provide a device of the character described in which an accurate regulation of the combustion may be obtained independently in each of a plurality of burners fed from a common reservoir, and in which the adjustable part is securely supported in all positions and reinforced against accidental movement or injury, and all danger of leakage avoided.

An embodiment of the invention is illustrated in the accompanying drawings, in which Figure 1 is an outline or diagrammatic front view of a reservoir and two burner troughs in operative relation embodying the improvements. Fig. 2 is an enlarged back elevation of one of the burner troughs and adjacent parts, mounted on the main fuel supply pipe. Fig. 3 is a side elevation of the parts shown in Fig. 2. Fig. 4 is a horizontal section on the line 4-4 of Fig. 3, looking in the direction indicated by the arrows in that figure. Fig. 5 is a view similar to Fig. 2 of a modified form of flexible supply pipe.

The supply pipe A communicates with the reservoir B through the branch pipe C and with each burner through a flexible pipe D, and may be mounted in any suitable stove frame. The reservoir is of the ordinary student lamp type and made of any desired form. The burner trough E is of annular form and is provided with the usual asbestos wick or "lighting ring" F.

In the preferred form (Fig. 2) the burner supply pipe is shaped like a spiral spring, and at its upper end communicates with the

trough or bowl E while its lower end communicates with the supply pipe A through a connection comprising the frame G rigidly connected with the supply pipe, the hollow 5 nipple H on the end of the burner pipe and the compression screw J by which it is held securely seated in the oil passage G'. In this manner communication between the burner and the main supply pipe is established, through a flexible conduit which permits the burner to be raised and lowered, without affecting the flow of liquid between the two or causing danger of leakage. On the pipe A at the junction of the coiled 10 burner tube is mounted a frame K, preferably made of a piece of sheet metal having its ends K' turned down and recessed so as to form a saddle resting on the upper surface of the said supply pipe, and its sides K² 15 and K³ turned down so as to lie on the sides of the pipe. It is secured against turning movement on the pipe by having the oil passage pipe G' passed through it and being clamped between this pipe and the frame 20 K which is threaded on the exterior of the former.

The part K² has an interned slotted flange K⁴, and in the upper horizontal portion of K is a slot of similar form and alined therewith, so that the two slots will receive the rigid upright support L for the burner trough and permit it to slide vertically therein. The upper end of the support L has an extension L' projecting inwardly and upwardly and secured to the burner trough, and at its lower end, and below the slotted flange K⁴, it has a pin L³ which extends through the volute slot M' of the rotary disk M. In this manner provision is made 30 for raising and lowering the sliding support L, and with it the burner trough, and holding them securely in all positions.

The disk M is mounted on the part K by having the pivot bolt N passed through the 40 depending portions K² and K³ and secured against retraction by the nut N'. The disk is rigidly connected with the bolt, and to the outer end of the bolt is keyed a handle O by which the said bolt and the disk may 45 be rotated. The bolt N also passes through a slot L² in the reciprocating support L, and the said bolt turns freely in the part K, so that the disk may rotate freely and the said support move freely up and down and at 50 the same time be securely held against movement in all other directions.

It will be seen that rotation of the disk in clockwise direction lowers the burner trough, and that rotation of the same in the 55 opposite or counter-clockwise direction raises the trough, and that any vertical pressure or strain on the burner or the sliding support L is resisted by the edges of the slot M', in which the pin L³ fits snugly. This 60 is the case at all times and with the pin at

all points in the slot or way. Lateral pressure or strain on the parts is resisted by the frame K, in the slots of which the support L fits without room for play.

In order to facilitate the use of the raising and lowering device for regulating or extinguishing the flame of the burner suitable markings may be placed on the disk M to indicate the effect of different positions thereon, the head of the pin L³ being formed 70 into a pointer directed toward the said markings. Thus with the pointer opposite the numeral 4 the burner trough is in its highest position, so that the oil will drain therefrom, owing to the fact that in this position it 75 is above the maintained oil level of the tank, and the flame will be extinguished. With the pointer opposite the numeral 1—in the opposite end of the slot—the trough will be in its lowest position and the level of oil 80 near the top of the trough. This position enables the operator to flood the burner trough quickly and saturate the wick for lighting. The numeral 2 indicates the position for high flame and the numeral 3 the 85 position for low flame; and any desired positions between the two extremes may be used.

In the modification of Fig. 5 the burner pipe D' is coiled substantially in a vertical plane, and it will be understood that various 90 other forms may be employed. With this form the other parts and their arrangement is the same as in the preferred form.

In operation the disk M is rotated until the pin L³ is at or near the outer end of 100 the way M', and the burner trough thus lowered to the flooding point. The wick F is then lighted, and the flame may be adjusted to any desired height by turning the disk in counter-clockwise direction. When 105 it is desired to extinguish the flame, the disk M is rotated until the pin L³ is at or near the inner end of the way M', thus raising the trough above the maintained oil level and draining it.

Various changes in the details of construction and arrangement herein shown and described may be made without departing from the scope of the invention.

What we claim is:

1. The combination with a reservoir having a maintained oil level and a burner trough, and an oil supply conduit communicating between said reservoir and trough, of means for raising and lowering the trough with respect to the said oil level comprising a flexible pipe at the end of the conduit nearest the burner, a sliding support connected with said trough and a rotary member with which said support is movably 115 connected.

2. The combination of a reservoir having a maintained liquid level, a main supply pipe communicating therewith and extending laterally therefrom, a burner trough and 120

5 a branch supply pipe extending from said main supply pipe to the trough, said branch supply pipe being composed of a single piece of tubing bent between its ends and thereby made flexible and permitting the burner trough to be moved toward and from the main supply pipe.

10 3. The combination of a reservoir having a maintained liquid level, a main supply pipe communicating therewith and extending laterally therefrom, a burner trough and a branch supply pipe extending from said main supply pipe to the trough, said branch supply pipe being composed of a single piece 15 of tubing bent between its ends and thereby made flexible and permitting the burner trough to be moved toward and from the main supply pipe, and means for moving the said burner trough comprising a rigid member and a support therefor, and a movable connection between the said rigid member and its support.

20 4. The combination of a reservoir having a maintained liquid level, a main supply pipe communicating therewith and extending laterally therefrom, a burner trough and a branch supply pipe extending from said main supply pipe to the trough, said branch supply pipe being composed of a single piece 25 of tubing bent between its ends and thereby made flexible and permitting the burner trough to be moved toward and from the main supply pipe, and means for moving the burner trough comprising a support, a member connected with said support and the burner trough, and means for moving the said member on its support.

30 5. The combination of a reservoir having a maintained liquid level, a main fluid supply pipe extending therefrom, a burner trough, a branch supply pipe connecting said trough and main supply pipe, said branch supply pipe being flexible and permitting the trough to be moved to different positions 35 with respect to said main pipe, and means for moving said trough comprising a supporting member connected with the trough, a support for said member on a rigid part and means for moving said supporting member on its support.

40 6. The combination of a reservoir having a maintained liquid level, a main fluid supply pipe extending therefrom, a burner trough, a branch supply pipe connecting said trough and main supply pipe, said branch supply pipe being flexible and permitting the trough to be moved to different positions 45 with respect to said main pipe, means for moving said trough comprising a supporting member connected with the trough, a support for said member on a rigid part and means for moving said supporting member on its support, comprising a part extending 50 from the supporting member, a rotatable member and a sliding connection between

said rotatable member and extending member, a cam surface on said rotating member with which the extending member is in contact whereby rotation of the former causes angular movement of the latter.

70

7. The combination of a fluid reservoir having a maintained liquid level therein, a main supply pipe extending therefrom, a plurality of burner troughs, a branch supply pipe secured to each burner and communicating with the main supply pipe, said branch supply pipe being curved intermediate their extremities and thereby being made flexible to permit the troughs to be raised and lowered, and means for raising and lowering a trough comprising a rigid trough supporting member, a sliding connection between said member and the supply pipe, and means for moving the said member vertically and automatically holding the same in different positions against vertical strain.

75

8. The combination of a fluid reservoir having a maintained liquid level therein, a main supply pipe extending therefrom, a plurality of burner troughs, a branch supply pipe secured to each burner and communicating with the main supply pipe, said branch supply pipes being curved intermediate their extremities and thereby being made flexible to permit the troughs to be 80 raised and lowered, and means for raising and lowering a trough, a disk, a cam surface on said disk, a member connected with a trough and having a portion in contact with said cam surface, whereby movement of the 85 disk moves the trough to different positions.

90

9. The combination of burner troughs, a liquid fuel tank having a maintained oil level, a main fuel supply pipe extending from said tank, flexible branch pipes secured to the troughs and to the main supply pipe, each composed of a single piece of tubing, and means for raising and lowering a burner trough comprising a movable member, a cam way in said movable member, a connection between said cam way and a burner trough, and means for moving the said member bearing the cam way and thereby causing movement of 100 the trough in directions angular to the cam way.

105

10. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate 110 its ends.

110

11. The combination of a liquid fuel reservoir, a main fuel supply pipe extending therefrom and adapted to supply liquid fuel to burners, burner troughs and a branch sup- 120

130

- 4
- 5
12. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate its ends. 50
- 10 12. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate its ends, and means for raising and lowering its ends, and means for raising and lowering 55
- 15 the trough without disconnecting or affecting the continuity of the said tube. 60
13. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate its ends, 65
- 20 13. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate its ends, 70
- 25 means for raising and lowering the trough without disconnecting or affecting the continuity of the said tube, comprising a movable member secured to the trough, and means for moving the said member and the 75
- 30 trough toward and from the main supply pipe. 80
14. The combination of a liquid fuel reservoir, a main fuel supply pipe extending therefrom and adapted to supply liquid fuel to burners, a burner trough and a branch supply conduit consisting of an uninterrupted tube secured at one end to the main supply pipe, and at its other end to the trough, formed in convolutions intermediate 85
- 35 its ends, means for raising and lowering the trough without disconnecting or affecting the continuity of the said tube, comprising a movable member secured to the trough, and means for moving the said member and the 90
- 40 trough toward and from the main supply pipe and for holding the said movable member automatically in different positions. 95
- 45 15. The combination of a liquid fuel res-
- ervoir, a main fuel supply pipe extending therefrom and adapted to supply liquid fuel to burners, a burner trough and a branch supply conduit consisting of an uninterrupted tube secured at one end to the main supply pipe, and at its other end to the trough, formed with sinuosities intermediate its ends, and a movable member mounted on a fixed part and connected with the trough whereby the said trough may be moved with respect to the main supply pipe without affecting the continuity of the tube, 60
- 50 said movement of the trough being permitted by the flexibility of the tube. 65
16. The combination of a burner trough, a liquid fuel supply pipe, a flexible pipe connecting the trough and the fuel supply pipe, 70
- 55 and means for raising and lowering the trough comprising a disk rotatably mounted on a fixed part, a spirate slot in said disk, a key in said slot adapted to be moved radially of the disk through rotation of said disk and a connection between said key and the trough. 75
17. The combination of a burner, a reservoir, a rigidly mounted liquid fuel supply pipe leading from said reservoir, and a flexible branch supply pipe communicating between said first supply pipe and the burner, 80
- 60 said branch supply pipe extending upwardly from the first pipe and being lengthwise extensible. 85
18. The combination of a burner, a reservoir, a rigidly mounted liquid fuel supply pipe leading from said reservoir, and a flexible branch supply pipe communicating between said first supply pipe and the burner, said branch supply pipe extending upwardly from the first pipe and being lengthwise extensible, and means for raising and lowering the burner without moving the first supply pipe. 90

Witness our hands this 9th day of April, 1918, at the city of Milwaukee, in the county of Milwaukee, State of Wisconsin.

JOHN S. BRENNAN.
ALBERT J. LINDEMANN.
